UNITED STATES PATENT OFFICE.

NIKOLA TRBOJEVICH, OF DETROIT, MICHIGAN, ASSIGNOR TO GLEASON WORKS, OF ROCHESTER, NEW YORK, A CORPORATION OF NEW YORK.

MACHINE FOR GENERATING GEARS.

Application filed May 7, 1923, Serial No. 637,372, and in Canada April 19, 1923.

The invention relates to hobbing of spiral bevel gears, and in particular to a hobbing machine embodying my novel method of gear generating, which method was described at 5 some length in my Patent Numbers 1,465,149, 1,465,150 and 1,465,151, issued August 14, 1923.

In the drawings:

Figure 1-5 and 7-8 are geometrical diagrams illustrating the theory of the process 10 of generating,

Figure 6 is an elevation of a tapered hob 15 engaging a spiral bevel gear,

Figure 9 is the plan view of the hobbing 20 machine the hob spindle and work spindle being shown in a common plane for clearer illustration of the mechanism.

Figure 10 is the sectional view of the feed 25 spindle on the line 10-10 of Figure 9,

Figure 11 is a front elevation of the hob 30 and feed spindles, the hob axis being swivelled about the axes 50.

Figure 12 is a rear end view of the 35 machine,

Figure 13 and Figure 14 show the necessary 40 adjustments of the pitch cone apexes in the common tangent plane.

In order fully to understand the operation 45 and the specific features of this machine it is necessary briefly to recapitulate the basic principles of my method of gear cutting.

It is a well known fact that the common 50 spur gears whether of the straight or the helical tooth type, may be produced by the hobbing process. From theoretical considerations, it may be stated that the only criterion determining the possibility of hobbing a gear of any description is whether or not said gear meshes with a worm. Because if 55 it does, the gear may be (theoretically) hobbed, first, by making a steel helical cutter an exact counterpart of the worm, second, by bringing said cutter in a tangential relation with the gear blank and by rotating both 60 elements in a timed relation, and third, by imparting a relative feed movement, or a movement of translation to the cutter.

The above named criterion i. e., the meshing 65 of the gear with a worm, needs further explanation. Generally speaking there are possible two kinds of meshing or engagement between two gears, the rolling engagement when the pitch surfaces roll on each other

without sliding and the axes are co-planar, and the sliding engagement when the pitch 55 surfaces slide and the axes are non intersecting and non parallel. The two kinds of engagement may also be distinguished by the relation of their respective developments in the common tangent plane. In the first 60 case (the rolling engagement), both gears produce the same identical development or in other words, the development of one gear is completely superposed upon the development of the other. In the sliding engagement 65 the two developments are distinct, and the superposition is only partial along a certain common generator of the two systems of tooth curves. Naturally, for the purposes of hobbing only the sliding engagement is 70 of interest.

This principle is illustrated in the Figs. 1-4. Fig. 1 shows two spur gears B_1 and B_2 in mesh, while their development in the common tangent plane T is the rack B' in 75 Fig. 1^a. In Fig. 2 two helical gears C and D mesh with sliding engagement, and their respective developments C' and D' are shown in Fig. 2^a. Fig. 3 shows two bevel gears E_1 and E_2 in a rolling contact, said 80 bevel gears having the common development (or crown gear) E' Fig. 3^a. A bevel worm drive, (my discovery) is shown in Fig. 4. The tapered worm F meshes with a spiral 85 bevel gear G with a sliding contact. In development (Fig. 4^a) the imaginary crown gears F' and G' are distinct and are superposed in such a manner that their base circles c' and c'' touch and the common generators g' coincide. It is to be noted that 90 in all four types of engagement the generators g' always coincide in development.

This method of gear cutting is based upon a mathematical discovery that there is a certain family of spirals which if used as 95 longitudinal tooth curves produce a system of bevel gears capable of meshing together in a dual fashion, namely with intersecting axes (a rolling engagement) as shown in Fig. 3 and Fig. 3^a and with axes non- 100 intersecting and non-parallel and sliding action as shown in Figs. 4 and 4^a. Said spirals form the family of general, or modified involutes of circle and include the common involute of circle together with its 105 tangential curves or followers, the extended

and the abridged involutes, and the Archimedean spiral.

The derivation of a modified involute from a parent involute is shown in Fig. 5. On the evolute d a straight line n_1 is rolled without sliding. A point A_1 of said line describes the involute e . To this involute a series of tangents such as $A_1 A_2$ are drawn, and the distance $A_1 A_2$ is made equal to a constant p . The locus f thus described is a modified involute. An important property of these curves is that if any number of involutes e and any number of its derivatives f are drawn from the same evolute d , the normals n_1, n_2 etc. of the corresponding points A_1, A_2 etc. will always pass through the same point A of the evolute.

Referring now to the modified involutes of circle, they all can be expressed by the following mathematical equation:—

$$x = (a+p) \cos \phi + a \phi \sin \phi$$

$$y = (a+p) \sin \phi - a \phi \cos \phi$$

where a and p are constants and ϕ is a parametric angle. In particular a is equal to the base radius while p is the modification as shown in Fig. 5. The modified involute as defined by the above equations has two special cases, one of which is important as it makes this invention practicable. First, when $p=0$ the curve reduces to a common involute of a circle. Second, when $a+p=0$ the curve reduces to an Archimedean spiral, that is to a spiral of constant lead. This latter property is the important one, because we are now able to include a tapered hob of constant pitch (an Archimedean spiral in development) in this system of spiral bevel gearing.

According to the geometric laws governing this system of gearing two bevel gears will mesh in an apex to apex position (Fig. 3 and Fig. 3^a) if both a and p are respectively the same, for both developments. They will mesh with a sliding action as shown in Figs. 4 and 4^a if the values of a are different while the modifications are the same in absolute value for both. The last case may be still further subdivided. If p is of the same design (either positive or negative) for both developments $F' G'$ (Fig. 4^a) the base circles c' and c'' touch internally. If the sign of p is positive for one and negative for the other, said base circles touch each other externally.

An Archimedean spiral (as I have shown in my co-pending applications) is nothing but a modified involute having a base radius equal to its polar subnormal, and a modification equal to the negative value of said subnormal. Thus, an Archimedean spiral may be used to generate modified involutes having any base radius a whatever; however, all those involutes must have the same modification p equal in absolute value to said

subnormal. Furthermore, if the base circles of the generated gear and of the hob touch each other externally in development, the produced curves will have a positive modification, that is, they will be extended involutes. They will be abridged involutes if said base circles touch internally. In my method I prefer to generate extended involutes, as in that combination the teeth of the hob move in an opposite direction to the rotation of the blank which is a desirable condition in milling. Figure 6 shows a tapered hob H of constant pitch, in engagement with a spiral bevel gear J of the extended involute type. The rack element g' coincides with the axial plane of the hob H . When said generator g' engages the teeth of the gear J it does so along a geodesic helix drawn on the pitch cone of the gear.

It will be seen that the hob shown in Figure 6 is similar in every respect to the ordinary spur hob except that it is tapered. It is provided with a number of axial gashes h' and the remaining teeth j' are relieved by a movement of a relieving tool in an axial plane, and perpendicularly to the side of the cone. The cone angle is preferably 30° (as shown), as that angle is about the most satisfactory for ordinary commercial purposes. For the same reason, the pressure angle is selected as 20°. It will be understood that if the same cone angle is selected for all hobs, the construction of the hobbing machine is simplified, as the tool head of the machine may be built to accommodate that particular cone angle.

Figure 7 shows the superposed tangent plane developments J' and H' of a spiral bevel gear of the extended involute type, and of an Archimedean spiral hob, respectively. Said figure shows graphically that if this method of gear generating is to be theoretically correct it is necessary that the pitch cone apex of the hob be placed at K , and that of the gear at L , and the distance $K L$ be made equal to $a+p$ the sum of the base radii of the gear and the hob. The rack generator g' is always perpendicular to the apex distance $L K$ at the point K , consequently it maintains its parallel relation to the parent involute generator g passing through the point of tangency M of the base circles c_1 and c_2 . The point M lies on the evolutes (base circles) to both systems and is therefore analogous to the point A shown in Figure 5. It is easily proved mathematically that the lines $N_1 M$, $N_2 M$, $N_3 M$, are common normals to the systems of curves H' and J' at the points N_1 , N_2 and N_3 . Therefore, there is a complete tangency between the corresponding tooth curves, and that tangency is maintained when the two developments H' and J' are rotated about their respective centers K and L at such a ratio that the two base circles c_1 and c_2 roll

on each other without slipping. In that case the points N_1 and N_2 , etc. of the rack generator g' will have a linear translation equal to the circumferential velocity of said base 5 circle c_1 and c_2 in the direction indicated by the arrow. It will be noticed by inspecting said Figure 7, that while there is a complete tangency of the curves H' and J' along the generator g' there is also what might be 10 termed a secondary interference and crossing of said curves further away. That interference, however, is only apparent, and would take place only if both the gear and the hob were plane developments, that is, 15 crown gears. But in the present method of gear cutting the hob is always pinion shaped, and the cone angle and the pressure angle of the hob are always so selected that secondary interference does not occur even if 20 crown gears are being cut.

From the preceding outline of the theory of engagement between the hob and the gear, a hobbing machine may be designed.

The characteristic feature of any hobbing 25 machine embodying this invention is that it possesses three main axes or spindles, two of which are intersecting while the third is in a skew position (non-intersecting and non-parallel) with respect to either. In particular, Fig. 8, shows the relative positions of 30 said three axes; the feed, the gear, and the hob axes. The diagram is self-explanatory as far as it goes. In addition, it should be remembered that in order to generate 35 rect gears, the pitch cone apexes of the hob and the gear must be at the points Q and P respectively. Furthermore, either the hob axis, or the gear axis, must be rigidly attached to the feed axis. In my preferred 40 construction, the hob axis is so attached. Hence, when the feed axis is rotated in a direction as indicated by the arrow it carries the hob axis with it toward the gear axis. Therefore, the hob performs a planetary 45 motion, and its apex describes the modified base circle in the tangent plane. As it was formerly stated, the gear blank always rotates against the hob when extended involutes are generated. It is also possible to 50 select the direction of the feed in such a manner that the large end of the hob always enters the blank first. This is of considerable practical importance, as then the large 55 end of the hob performs the largest part of the work of the metal removing, thus rendering a tapered hob even more efficient in that respect than the ordinary spur hob.

Figure 9 to Figure 12 show the various 60 views of a typical hobbing machine embodying this principle of gear generating.

The general organization of such a machine includes three spindles rotatable in a timed relation together with means for adjustment of their relative positions with respect to the tangent plane. To this a com-

pensating gear or differential may be added to facilitate the proper timing of said three shafts. The last named mechanism is not absolutely necessary for the correct operation of this machine as it is possible to 70 connect three shafts with only two sets of change gears in any desired and positive ratio. The addition of the compensating gear, however, permits of engaging or disengaging the feed spindle at any instant, 75 and as often as it may be desired without disturbing the proper meshing of the hob and the blank.

It will be noted that the above is nothing but a most general type of the ordinary 80 hobbing machine. In other words, the common hobbing machine is but a special case of this machine, adapted to cut spur gears, that is, modified involute gears of infinite base radius, infinite modification and zero 85 cone angle. In that case, the hob also must have an infinite modification, or polar subnormal, from which it follows that the cone angle of the hob must be zero, that is, a spur hob of constant pitch is used. In my method, 90 the feed is along a circular arc drawn from the apex of the gear. This feature translated into the well known spur system means that the feed of the hob is along a straight line, that is, a circular arc having 95 an infinite radius. The analogy may be carried still further and goes to prove that my invention consists of broadening and generalizing the principle of ordinary gear hobbing in such a manner as to include the 100 bevel gears also. Thus, according to this theory all hirable gears are produced by a hob of constant pitch and mesh with a rack 105 element of constant pitch along a series of geodesic lines.

Referring now to Fig. 9 which shows the plan view of my improved hobbing machine, the driving pulley 20 is housed in the bearings 21 and 22, cast integral with the bracket 23 (more fully shown in Fig. 12). At the 110 end of the pulley shaft 24 a change gear 25 may be keyed and clamped by means of a hexagon nut and washer, as shown. Said change gear co-operates with another change gear 26 mounted above the gear 25 at a fixed 115 center distance, on the end of the shaft 27. Thus, by increasing the number of teeth in the first change gear 25, and by correspondingly reducing that number in the gear 26, the speed of the whole machine may be increased relatively to the angular velocity of the driving pulley 20. The transverse shaft 27 is mounted in two suitable bearings 28 and 29 cast integral with the bracket 30, which bracket also carries the bearing 31 holding the bevel gear 32, the function of 120 which gear will be explained later on. On the shaft 27 two mitre gears 33 and 34, held together with a splined sleeve 35, are placed, and may be shifted longitudinally and se-

curely held in any such longitudinal position, thus permitting the mitre 36 to be driven either by the gear 33 or by the gear 34. In that manner the direction of the rotation of the entire machine may be reversed.

The cutter drive and adjustment.

The mitre 36 is keyed to the end of the shaft 37. One end of said shaft is housed in the bearing 38 while the other end is splined and engages the corresponding sleeve of the gear 39. Said gear is housed in, and carried by the feed cylinder, cradle, head, face plate, or barrel 40, and remains in engagement with the shaft 37 when said cylinder is either moved lengthwise or rotated. From the sun gear 39 the rotation is transmitted to the planet idler 41 and the planet gear 42, both carried in the rear wall of the said cylinder 40. The pinion shaft 43 is also housed in the cylinder 40 and has two gears keyed thereto, the planet gear 42 and the bevel pinion 44. The last named pinion mates with the spindle bevel gear 45, slidably mounted on the cutter spindle 46 to the end of which the hob or cutter 47 is securely mounted. The manner of mounting of the hob on the spindle 46 may be accomplished in many various ways. In my preferred construction, the hob has a tapered hole, and a threaded shank or boss near the large end (Fig. 6) into which boss a wide keyway or slot is cut. A corresponding hob arbor having a tapered shank snugly fits into the front end of the spindle 46 and the hob is drawn tightly against the same arbor by means of a threaded ring 48, while the hob arbor is drawn into the spindle by means of a suitable draw bolt.

The adjustment of the hob apex with respect to the tangent plane will best be understood from Fig. 9 and Fig. 11. The front end of the feed cylinder 40 is machined to a plane exactly perpendicular to the axis of said cylinder and therefore parallel to the tangent plane Y—Y of the machine. A swivelable cutter base 49 is mounted on said front end of the cylinder 40 and may be swiveled about the pivot 50, concentric with the pinion 44. The upper surface of said base is machined to a way 49^a including exactly the same angle with the front end of the cylinder 40 as the cone angle of the hob to be used (in our case 30 degrees). Therefore, when the cutter head proper 51 is mounted on the said top slide of the base 49, the hob 47 is always either tangent, or parallel to the plane Y—Y irrespective of the angular adjustment about the pivot 50 or the longitudinal adjustment in the inclined plane. The angular adjustment is effected by releasing the bolts 52 and swiveling the base to a predetermined angle from the center line of the machine either to the right (as shown), when right hand

gears are generated or to the left—for left hand gears, and then tightening the bolts 52 against the corresponding T slots 53. As the distance of the pivot 50 from the center line of the machine is a constant of the machine, and thereby known, the angle to which the base 49 is to be swiveled to suit any particular modified base radius ($a+p$) may be easily determined by calculation, as it will be understood.

The longitudinal adjustment is accomplished first by releasing the bolts used for clamping the cutter head 51 to the base 49 and the spindle 46 to the bevel gear 45 by moving the head 51 in its slide by means of an accurately cut screw 54 and the graduated dial 55 until the apex of the hob falls into its proper position, the point of tangency of the cutter axis with the base circle, and by clamping the head and the spindle in that position. It is to be noted that during said longitudinal adjustment the bevel gear 45 does not move longitudinally with the cutter head 51 but stays in engagement with its mating pinion 44.

There is one more adjustment necessary, namely to regulate the depth of the cut, or, to bring the pitch cone of the hob 47 in tangency with the plane Y—Y. To accomplish that, the main worm gear 56 is not directly bolted to the feed spindle 40 but it has three equally spaced bearings 57 built in it to house the corresponding three drive screws 58. On the outer ends of said three screws, three planetary gears 59 are keyed, said gears being constantly in mesh with the sun gear 60, mounted on a shank 61 integral and concentric with the worm gear 56.

The sun gear 60 is preferably made integral with the bevel gear 62, the latter engaging the bevel pinion 63. Said pinion is keyed to a shaft which is housed in the bearing 64, and carries on its other extremity a handwheel 65 keyed thereto. The other ends of the screws 58 are threaded and engage the corresponding internally threaded bosses 66 of the cylinder 40. Three check nuts 67 serve to clamp said screws to the body of the cylinder 40.

The worm gear 56 is housed in the upper and lower ring castings 68, and 69, the walls of which are accurately machined on the inside to hold the worm gear 56 in position, and also to act as thrust bearings for the same. In order to make an adjustment for the depth of cut, the check nuts 67 are released and the hand wheel 65 operated. Due to the fact that the worm gear 56 cannot move lengthwise, and also is prevented from turning by its mating worm 70, the screws 58 will turn in their respective bearings 57 and the cylinder 40 will move forwards or backwards, depending on the direction in which the handwheel 65 is rotated. After the adjustment for depth of cut is 130

made, the check nuts 67 are tightened, and the hob is ready for cutting of the gear.

The feed mechanism.

5 Mitre 32 is driven by the mitre 71 keyed to the shaft 37. Said mitre 32 is keyed to a shaft 72 housed in two suitable bearings 31 and 73. Shaft 72 is inclined to the central plane of the machine to an angle of 10 about 45 degrees and carries the bevel pinion 74 keyed to its lower end. Bevel gear 75, on the shaft 76, engages said pinion 74 and transmits the rotation to the worm 77 mounted on said shaft 76, and also to the 15 worm gear 78. The shaft 79, carrying the last named worm gear, is mounted in the bearing 80 and it carries on its outer end the first feed change gear 81. Change gears 82 and 83 are mounted on a swing sector 20 (not shown) and the last gear 83 engages the driven change gear 84, mounted on the hand wheel shaft 85. Said shaft is mounted in the bearings 86 and 87 and in the bearings 88 and 89 underneath the main worm 25 gear 56 (Fig. 11) and carries mounted thereon besides the change gear 84, also the first differential change gear 90, suitable thrust collars and the main drive worm 70. The main worm gear 56 drives the feed 30 spindle by the medium of drive screws 58, as previously explained.

The change gear 84 may be either keyed to the shaft 85, or disengaged, as desired, by means of a hand operated clutch (not 35 shown). Thus the feed cylinder 40 may be rotated at any desired rate by power, by properly selecting the feed change gears 81, 82, 83, and 84 and again, it may be operated by hand through the hand wheel 91.

40 *The differential.*

The first differential change gear 90 engages the change gear 92 from which the rotation is transmitted through change 45 gears 93 and 94, the shaft 95 housed in the bearing 96, to a worm of comparatively large diameter and small angle of thread 97. Said worm 97 engages the gear 98, and thereby controls the rotation of the first differential sun gear 99 and is rotatable with 50 respect to the shaft 76. The differential spider 101 is keyed to the end of the shaft 76 and kept there in position by means of a thrust collar 102. In said spider 101 four 55 bearings are formed to permit of mounting there of the planet pinion shafts 103, carrying two sets of planet pinions keyed on their respective ends, namely, the pinions 104, engaging with the sun gear 99, and the pinions 105, engaging with the driven sun gear 106.

The action of the differential gear employed in this machine is fully analogous to that employed in some of the ordinary gear hobbing machines designed for cutting of 60 helical spur gears. The object is, as already

stated, to impart to the gear blank the sum (or the difference) of two rotations simultaneously; first, to keep the gear blank in timed relation when the hob is rotated about its own axis, and second, to maintain said 70 timed relation when the hob is bodily translated in the tangent plane, to produce the feed. These two elements of rotation must be, naturally, compounded correctly and continuously at every instant during the process 75 of gear cutting, and the arrangement as shown in Fig. 9 and Fig. 11 accomplishes that purpose.

If the pulley 20 is held fast, and the feed gear 84 disengaged, the spider 101 will remain stationary when the hand wheel 91 is operated. Through the change gears 90, 92, 93, 94, the worm 97, the worm gear 98, the sleeves 100, the sun gear 99, the differential pinions 104 and 105, and the drive sun gear 80 106 a rotation is imparted to the shaft 107 and thence to the blank. Again through the worm 70 and the gear 56 the feed spindle 40 is simultaneously rotated which imparts a movement of translation to the hob 47 as 85 previously described. By a proper selection of the differential change gears 90 to 94 this element can be compensated for, therefore. Regarding the selection of the last named 90 change gears it should be noted that there is a peculiar factor (which I termed as the "epicyclic factor") that enters into calculation and is due to a peculiar feature of 95 design of this hobbing machine, a counterpart of which cannot be found in the ordinary 100 gear hobbing machine. When the feed cylinder 40 is rotated, it may be considered that the tangent plane Y—Y is carried with it, that is, rotates with it. Hence, the gear blank should be rotated as if it were rolling 105 with said tangent plane without slipping. However, when said cylinder 40 is rotated, the hob 47 also will slightly rotate on its axis even if the pulley is held fast due to the fact that the sun gear 39 is stationary and 110 the drive gears 41, 42, 44, and 45, receive a rotation owing to their planetary position with respect to said gear 39. Thus, the (imaginary) rotation of the tangent plane 115 Y—Y is slightly different from that of the cylinder (the difference is under ordinary conditions about one per cent) and for close work this must be taken into consideration when a calculation for change gears is made.

In order to examine the second element 120 of rotation transmitted by the differential mechanism, we again disengage the feed gear 84, but now hold the handwheel 91 fast, and rotate the pulley 20. In that case the sun gear 99 remains stationary and the differential mechanism acts as if it were 125 an ordinary speed reducing epicyclic gear. The shaft 76 being keyed to the spider 101 rotates the same, and due to the fact that the sun gear 99 is stationary, and has a dif- 130

ferent number of teeth from the driven sun gear 106, (in our case 106 has a fewer teeth than 99) the shaft 107 will rotate at a reduced rate, and in the opposite direction relatively to the shaft 76. The index change gears (which will be described presently) are so selected that the hob and the gear blank rotate in a reverse ratio to their respective numbers of threads or teeth, the same as in any other hobbing machine.

It will also be seen that if both elements of rotation described above are imparted to the differential simultaneously, they will not interfere with each other, but will be correctly and continuously compounded at every instant and the shaft 107 will always receive the sum or the difference, as the case may be, of the two rotations.

The work drive and adjustment.

The arrangement for holding and adjusting the blank in this machine is designed along well established lines found in the majority of the bevel gear cutting machines. The only novelty will be found in the increased range of angular adjustability of the work arbor. While in ordinary bevel gear cutters that range is usually 90° , in this case the range is 180° that is half a circle. By the virtue of this increased adjustability it is possible to generate in this machine commercial gears of all sizes within the range of machine, right or left hand, in such a manner that first, the hob always cuts on the upward swing of the feed cylinder; second the large end of the hob always enters first, and third the blank always rotates in the opposite direction (against the cut of the hob). The observation of these practical requirements in the design of this machine have greatly added to the utility of this method.

The shaft 107 carrying on one end the driven differential sun gear 106, and the mitre 108 on the other, is housed in two bearings 109 and 110. A cross shaft 111 carrying the mitres 112 and 113 on opposite ends, brings the rotation to the apex or center of the machine. A short vertical shaft carrying two mitres 114, transmits said rotation through the mitre 115, and the swinging shaft 116 to the index change gear 117. From there another change gear 118, keyed to the end of the splined shaft 119, is driven, thus imparting the rotation to the final drive pinion slidably mounted on the shaft 119 (not seen in Fig. 9) the final drive gears 120 and 120^a and the work spindle 121.

The blank to be cut 122 is mounted in the customary way on the face plate 123, and is drawn tightly against the same by means of the drawbolt 124. The work spindle 121 is mounted in two bearings 125 and 126 integrally cast with the upper work slide 127.

The lower work slide 128 may be swung about the apex of the machine on the semicircular table 129, the latter being provided with a number of circular T slots 130. The upper portion of the slide 128 is formed to a rectangular way, the axis or center line of which is always in a vertical plane passing through the apex of the machine, and the upper work slide 127 is fitted carefully in those ways so that the axis of the spindle will always pass through the apex of the machine, and be in the same horizontal plane with the axis of the feed cylinder 40. Hence no matter what angular or longitudinal position the work spindle is brought to, its axis is always co-planar with the feed axis, and intersects the tangent plane Y—Y at the apex of the machine.

From this description the adjustment of the gear blank will be understood. The lower slide is swiveled on the semicircular apron 129 until the pitch cone of the blank is parallel to the tangent plane Y—Y. In that position the lower slide is clamped against the T slots 130, with suitable bolts and nuts. Then the longitudinal adjustment of the cutter spindle is effected, that is, the pitch cone of the blank is brought into tangency with the plane Y—Y. A train of suitable index change gears is selected, and the blank is ready to be cut.

What I claim as my invention is:

1. In a gear hobbing machine, the combination of a work spindle and a hob spindle having their axes non-intersecting and non-parallel, a feed spindle for rotating one of said spindles about an axis intersecting the axis of said work spindle and in acute angular relation to the axis of said hob spindle, and means for rotating said three spindles to maintain a predetermined timed relation between said hob and work spindles.

2. In a gear hobbing machine, the combination of a work spindle and a hob spindle having their axes non-intersecting and non-parallel, means for rotating said spindles in predetermined timed relation, means for rotatively feeding one of said spindles about an axis intersecting the axis of the work spindle and in acute angular relation to the axis of the hob spindle, and compensating means for maintaining said timed rotation during the rotation of said feeding means.

3. In a gear hobbing machine, the combination of a work spindle, and a hob spindle having their axes non-intersecting and non-parallel, a feed spindle for rotating one of said spindles about an axis intersecting the axis of said work spindle and in acute angular relation to the axis of said hob spindle, and means for rotating said three spindles in a predetermined timed relation.

4. In a gear hobbing machine, the combination of a work spindle and a feed spindle

having their axes intersecting in a common plane, a hob spindle mounted on said feed spindle having its axis at an acute angle with a plane perpendicular with said feed axis and non-intersecting and non-parallel with the axis of said work and feed spindles, and means for rotating said three spindles in a predetermined timed relation.

5. In a gear hobbing machine, the combination of a work spindle and a feed spindle having their axes intersecting in a common plane, a hob spindle mounted on said feed spindle having its axis at an acute angle with a plane perpendicular to said feed axis and non-intersecting and non-parallel with the axis of said work spindle, means for rotating said work spindle and hob spindle in a predetermined timed relation, means for rotating said feed spindle, and compensating means for maintaining said timed rotation during the rotation of said feed spindle.

6. In a gear hobbing machine, the combination of a work spindle and a hob spindle having their axes non-intersecting and non-parallel, a feed spindle for rotating one of said spindles about an axis intersecting the axis of said work spindle and in acute angular relation to the axis of said hob spindle, means for adjusting the hob spindle in a plane transverse to the axis of said feed spindle, means for adjusting said work spindle in an axial plane relative to said feed axis, and means for rotating said three spindles to maintain a predetermined timed relation between said hob and work spindles.

7. In a gear hobbing machine, the combination with a feed spindle, and a work spindle having their axes intersecting in a common plane, means for adjusting said work spindle about the point of intersection of said axes, a hob spindle mounted on said feed spindle and having its axis in a plane at an acute angle to said feed axis, a tapered hob on said spindle, means for adjusting said hob spindle to set the apex of said hob a predetermined distance from said feed axis, means for rotating said hob spindle and work spindle in a predetermined timed relation, means for rotating said feed spindle, and compensating means for maintaining said timed relation during the rotation of said feed spindle.

8. In a gear hobbing machine, the combination with a work spindle and a feed spindle having their axes intersecting in a common plane, means for adjusting said work spindle about the point of intersection of said axes, a hob spindle mounted on said feed spindle and having its axis in a plane at an acute angle to said feed axis, means for rotatively adjusting said hob spindle in its plane to set the axis thereof a predetermined distance from said feed axis, means

for adjusting said hob spindle longitudinally 65 of the axis of said feed spindle, means for rotating said hob spindle and work spindle in a predetermined timed relation, means for rotating said feed spindle, and compensating means for maintaining said timed relation 70 during the rotation of said feed spindle.

9. In a gear hobbing machine, the combination of a work spindle and a feed spindle having their axes intersecting in a common plane, a hob spindle mounted on said feed spindle having its axis in a plane at an acute angle to said feed axis, means for rotating said hob spindle and work spindle in a predetermined timed relation, means for rotatively adjusting said hob spindle in its 75 plane to set the axis thereof a predetermined distance from said feed axis, means for rotatively adjusting said work spindle, and means for rotating said three spindles to maintain a predetermined timed relation between said hob and work spindles.

10. In a gear hobbing machine, the combination of a feed spindle longitudinally adjustable to provide for the depth of cut and rotatable about its axis to provide the feed motion, a hob spindle carried by said feed spindle having its axis intersecting a certain plane perpendicular to the feed axis, means for axially adjusting said hob spindle, an axially adjustable work spindle having its axis intersecting said feed axis, said work spindle being laterally adjustable with respect to said plane, a tapered hob upon said hob spindle having a cone angle such that it may be adjusted to a position tangent to 100 said plane, said hob being provided with cutter teeth arranged in an Archimedean spiral, means for adjusting said hob spindle to set the apex of said hob a predetermined distance from said feed axis, means for rotating said hob spindle and said work spindle to maintain a predetermined timed relation, and means for rotating said feed spindle to advance the hob across the work upon said work spindle.

11. In a gear hobbing machine, the combination of a work spindle and a hob spindle having their axes non-intersecting and non-parallel, a rotary spiral hob mounted upon said hob spindle, said hob being provided with cutting teeth of the modified involute type, means for rotating said spindles in such a manner that said hob and the work upon said work spindle are tangent to a common plane on opposite sides thereof.

12. In a gear hobbing machine, the combination of a pair of spindles, a rotary spiral hob mounted upon one of said spindles, a gear blank mounted on the other of said spindles, means for adjusting said spindles in acute angular relation such that said hob and said blank are tangent to a common plane on opposite sides thereof, and means

- for rotating said spindles in a timed relation and means for moving one of said spindles about an axis lying in the same plane as the other spindle.
- 5 13. In a gear hobbing machine, the combination of a work spindle, a hob spindle, a tapered hob of the modified involute type mounted upon said hob spindle, means for adjusting said spindles in such a manner 10 that the hob and work are tangent to a common plane on opposite sides thereof, means for rotating said spindles in a timed relation, and means for feeding said hob into said blank.
- 15 14. In a gear hobbing machine, the combination of a work spindle, a hob spindle, a tapered hob mounted upon said hob spindle, means for adjusting said spindles in an acute angular relation to each other and to a plane 20 tangent to the hob and the work, means for adjusting the distance between the corresponding points of intersection of said hob spindle and work spindle axes with said tangent plane, means for rotating said spindles in timed relation, and means for feeding the 25 hob into the blank.
15. In a gear hobbing machine, the combination of a work spindle, a hob spindle, a blank mounted on said work spindle, a hob 30 mounted on said hob spindle, said hob having cutting teeth of the modified involute type, the member mounted upon one of said spindles being of conical form, and means for adjusting said spindles into acute angular relation such that said hob and said blank 35 are tangent to a common plane upon opposite sides thereof, means for rotating said spindles in a timed relation, and means for feeding said hob into said blank.
- 40 16. In a gear hobbing machine, the combination of a work spindle, a hob spindle, a tapered hob of the modified involute type mounted upon said hob spindle, a bevel gear blank mounted on said work spindle, means 45 for adjusting said spindles in an acute angular relation to each other and to a plane tangent to said tapered hob and said conical blank, means for adjusting the distance between the corresponding points of intersection 50 of said hob spindle and work spindle axes with said tangent plane, means for rotating said spindles in a timed relation, and means for feeding said hob into said blank.
- 55 17. In a gear hobbing machine, the combination of a work spindle and a hob spindle, a blank mounted on said work spindle, a hob mounted on said hob spindle, said hob having cutting teeth arranged in a curve, the development of which is a modified involute 60 of a circle, means for adjusting said spindles such that said hob and said blank are tangent to a common plane upon opposite sides thereof, means for adjusting the distance between the respective points of intersection 65 with the tangent plane of the hob spindle and work spindle axes, means for rotating said spindles in timed relation, and means for feeding said hob into said blank.
18. In a gear hobbing machine, the combination of a work spindle and a hob spindle, a hob mounted upon said hob spindle, a blank mounted upon said work spindle, said hob and said blank being tangent to a common plane upon the opposite sides thereof, and said hob spindle and said work 70 spindle being arranged in acute angular relation to each other and to the common tangent plane, means for rotating said spindles in a timed relation, and means for simultaneously feeding the hob relative to the 75 blank to increase the depth of cut.
19. In a gear hobbing machine, the combination of a pair of spindles arranged in acute angular relation to each other, a hob upon one spindle having cutting teeth arranged in a curve, which in development is a modified involute of a circle, a blank mounted upon the other of said spindles, one of said members upon said spindles being of conical form and arranged tangent 80 to a plane which is tangent also to said other member, means for rotating said spindles in timed relation, and means for feeding the hob relative to said blank.
20. In a gear cutting machine, a blank support, a hob support, a hob having its cutting portions arranged in a spiral of Archimedes mounted on said support, means for positioning the hob and blank supports so that the axis of the hob is spaced from 85 the calculated base circle of the gear by a distance equal to the polar subnormal of the hob, means for rotating the hob and blank in timed relation and means for simultaneously imparting an additional relative movement between hob and blank about the apex of the blank.
- 100 21. In a gear cutting machine, a blank support, a hob support, a hob having its cutting portions arranged in a spiral of Archimedes, mounted on said support, means for positioning the hob and blank supports so that the axis of the hob is spaced from the calculated base circle of the gear to be cut, by a distance equal to the polar subnormal 105 of the hob, and means for rotating the hob and blank in timed relation.
- 110 22. In a machine for producing gears from conical gear blanks, a blank support, a hob support, means for positioning the hob and blank supports so that the pitch surfaces of hob and blank are tangent to a common plane with the axis of the hob projected into the tangent plane perpendicular to a line connecting the hob and gear 115 apexes and means for rotating the hob and blank in timed relation.
- 120 23. In a gear cutting machine, a blank

- support, a hob support, a hob, the normals to whose thread at the pitch surface in development intersect in a single point, mounted on said hob support, means for 5 positioning the hob and blank supports so that the point of intersection of the hob normals will lie on the imaginary base circle of the gear to be cut and means for rotating the hob and blank in timed relation.
- 10 24. In a gear cutting machine, a blank support, a hob support, means for positioning the hob and blank support so that normals to the hob threads and the teeth to be produced on the blank along a line lying 15 in the pitch surfaces of both hob and blank in development intersect in a single point, and means for rotating the hob and blank in timed relation.
25. In a machine for hobbing gears whose 20 teeth are curved longitudinally along spirals of the modified involute type, a blank support, a hob support, a hob of the modified involute type mounted thereon, means for positioning the hob and blank support so 25 that in development the base circles from which the longitudinal curvature of hob thread and blank teeth are derived are tangent and means for rotating the hob and blank in timed relation.
- 30 26. In a gear cutting machine, a blank support, a hob support, a hob, the normals to whose threads along a generatrix of its pitch surface intersect in a point, mounted on said hob support, means for positioning 35 the hob and blank so that in development the hob apex, the blank apex, and the point of intersection of the normals, all lie in the same straight line, and means for rotating the hob and blanks in timed relation.
- 40 27. In a gear cutting machine, a blank support, a hob support, a taper hob mounted on the hob support, means for positioning the hob and blank supports so that the pitch lines of hob and blank, in development, are 45 tangent along a straight contact line between the pitch surfaces of hob and blank, and means for rotating the hob and blank in timed relation.
28. In a gear cutting machine, a rotatable 50 blank spindle, a hob spindle, a taper hob mounted on said spindle, a supporting head, a hob carrier pivotally mounted on said supporting head and having an outer face inclined with reference to the supporting 55 head at an angle equal to the cone angle of the hob, supporting means for the hob spindle slidably mounted on said hob carrier, means for positioning the hob and blank so that their pitch surfaces are tangent to a common plane and means for rotating the hob and blank in timed relation.
- 60 29. In a gear cutting machine a rotatable blank spindle, a supporting head angularly movable about an axis passing through the 65 apex of the blank carried by said blank
- spindle, a drive shaft extending through said head and parallel to said head axis, a cutter base mounted on said head and pivotable about said drive shaft, a hob spindle rotatable on said cutter base, means 70 for operatively connecting the hob spindle with the drive shaft, and means for rotating the drive shaft, supporting head, and blank spindle in timed relation.
30. In a machine for cutting the teeth 75 of gears whose basis is a crown gear having teeth which are longitudinally of general involute curvature, the combination of a rotary blank support, a head angularly movable about an axis extending through 80 the apex of a blank carried by said support, a hob adapted to engage said blank, carried by said head and rotating about an axis that is offset from said head axis, and means for rolling said blank support and said hob 85 relatively to one another to form teeth along curves which adapt them to mesh with the curved teeth of said basic crown gear, substantially as set forth.
31. In a machine of the class described, 90 the combination of a rotary blank support, a head angularly movable about an axis extending through the apex of a blank carried by said support, a rotary hob adapted to engage said blank having its rotary axis 95 offset from the axis of said head, a member carrying said hob mounted upon the aforesaid angularly movable head, and means for adjusting said member to vary the degree of offset of hob axis and head axis, 100 substantially as set forth.
32. In a machine for hobbing bevel gears, a hob support, a taper hob mounted on the support, a blank support, means for positioning the hob support so that the axis of 105 the hob extends diagonally across the face of the blank, means for rotating the hob and blank supports in timed relation and means for imparting an additional relative rolling movement between the hob and blank 110 supports.
33. In a machine for hobbing bevel gears, a hob support, a hob of constant lead mounted on said support, a blank support, means for rotating hob and blank supports 115 in timed relation and means for imparting an additional relative movement between the hob and blank supports in the manner of a relative intermeshing rotation between a crown gear and the gear to be cut.
34. In a machine for cutting curved tooth bevel gears a rotatable blank support, a tool carrier, a rotary hob mounted thereon, means for positioning the blank support and tool carrier relatively to one another so that the pitch surfaces of the hob and blank are 120 tangent to a common plane means for rotating the hob and blank supports in timed relation and means for imparting an additional relative movement between the hob 125
- 65 apex of the blank carried by said blank

- and blank support about an axis perpendicular to said common plane of tangency.
35. A gear cutting machine, comprising a shaft, means for driving said shaft for rotating a conical blank carried thereby, a face plate rotatable about an axis intersecting the axis of said shaft, a second shaft carried by said face plate, a hob cutter carried by said second shaft, means for rotating 10 said face plate adapted to carry the hob cutter into changed position with respect to the blank, and means comprising a differential mechanism for rotating the hob cutter in continuously operative timed relation to 15 the rotation of the blank as the angular position of the second shaft is changed by the rotation of the face plate.
36. A gear cutting machine, comprising a shaft, means for driving said shaft for rotating a conical blank carried thereby, a face plate rotatable about an axis intersecting the axis of said shaft, a second shaft carried by said face plate and adjustable longitudinally thereon, a hob cutter carried by 20 said second shaft, means for rotating said face plate adapted to carry the hob cutter into changed position with respect to the blank and means comprising a differential mechanism for rotating the hob cutter in 25 continuously operative timed relation to the rotation of the blank as the angular position of the second shaft is changed by the rotation of the face plate.
37. A gear cutting machine, comprising a shaft adjustable by a swinging movement 35 in a plane about an axis at right angles to said plane, means for driving said shaft in its adjusted position for rotating a conical blank carried thereby, a face plate rotatable about an axis lying in said first named plane, a second shaft carried by said face plate and adjustable longitudinally thereon, a hob cutter carried by said second shaft, means for rotating said face plate adapted to carry 40 the hob cutter into changed position with respect to the blank, and means comprising a differential mechanism for rotating said second shaft and said hob cutter in continuously operative timed relation to the rotation 45 of the blank as the angular position of the second shaft is changed by the rotation of the face plate.
38. The method of cutting spiral bevel gears which comprises rotating a conical blank, swinging a hob cutter circumferentially across the conical face of the blank, applying power to the hob cutter through a uniformly operating driving mechanism for rotating the hob cutter, and applying 50 power additionally to the hob cutter through a differentially operating driving mechanism whereby the rotation of the hob cutter is kept in continuously operative timed relation to the rotation of the blank.
55. 39. In a machine for producing longitudi-
- nally curved teeth on the side face of a gear blank, a hob support, a hob of constant pitch rotatably mounted thereon, a blank support, and means for rotating the hob and blank in timed relation.
40. In a machine for producing longitudinally curved teeth on the side face of a gear blank, a hob support, a taper hob of constant pitch rotatably mounted thereon, a blank support, and means for rotating the hob and blank in timed relation.
41. In a machine for producing longitudinally curved teeth on the side face of a gear blank, a hob support, a taper hob rotatably mounted on said support, a blank support, means for adjusting the hob support so that the axis of the hob extends diagonally across the face of the blank in offset relation to the blank apex, and means for rotating the hob and blank in timed relation.
42. In a machine for producing longitudinally curved teeth on the side face of a gear blank, a blank support, a hob support, a hob of constant pitch mounted on said hob support, means for adjusting the hob support to position the hob so that its axis extends diagonally across the face of the blank in offset relation to the blank apex, and means for rotating the hob and blank in timed relation.
43. In a machine for producing longitudinally curved teeth on the side face of a gear blank, a blank support, a hob support, a taper hob of constant pitch rotatably mounted thereon, means for adjusting the hob support to position the hob with its axis extending diagonally across the face of the gear blank in offset relation to the blank apex, and means for rotating the hob and blank in timed relation.
44. In a machine for producing gears, the combination of means for supporting a tapered gear blank, a hob of constant pitch, means for rotating the hob and blank in intermeshing timed relation, and means for feeding the hob and blank relatively to each other.
45. In a machine for producing gears, the combination of means for supporting a tapered gear blank, a taper hob of constant pitch, means for rotating the hob and blank in intermeshing timed relation, and means for feeding the hob and blank relatively to each other.
46. In a machine for producing gears, a hob support, a taper hob rotatably mounted thereon, a blank spindle adapted to carry a tapered gear blank, a cradle on which the hob support is mounted, rotatable about an axis which lies in the same plane with the rotary axis of the blank spindle, and means for positioning the hob in definite offset relation to said plane.
47. In a machine for producing gears, a hob support, a hob of constant pitch rotat-

- ably mounted on said hob support, a rotatable blank spindle adapted to carry a tapered gear blank, a cradle, on which the hob support is mounted, rotatable about an axis which lies in the same plane with the rotary axis of the blank spindle and means for positioning the hob in definite offset relation to said plane.
48. In a machine for producing gears, a 10 hob support, a taper hob of constant pitch rotatably mounted on said hob support, a rotatable blank spindle adapted to carry a tapered gear blank, a cradle, on which the hob support is mounted, rotatable about an axis which lies in the same plane with the rotary axis of the blank spindle, and means for positioning the hob in definite offset relation to said plane.
49. In a machine for producing gears, 20 a rotatable blank spindle adapted to carry a tapered gear blank, a hob support, a taper hob rotatably mounted thereon, means for rotating the blank spindle, means for rotating the hob, and means for simultaneously moving the hob and blank relatively to each other about an axis which lies at an angle to the rotary axis of the hob.
50. In a machine for producing gears, a 30 rotatable blank spindle adapted to carry a tapered gear blank, a hob support, a taper hob of constant pitch rotatably mounted thereon, means for rotating the blank spindle, means for rotating the hob, and means for simultaneously moving the hob and blank relatively to each other about an axis which lies at an angle to the rotary axis of the hob.
51. In a machine for producing gears, a 40 rotatable blank spindle adapted to carry a tapered gear blank, a hob support, a hob of constant pitch rotatably mounted thereon, means for rotating the blank spindle, means for rotating the hob, and means for simultaneously moving the hob and blank relatively to each other about an axis which lies at an angle to the rotary axis of the hob.
52. In a machine for producing gears, a 50 hob support, a taper hob rotatably mounted on said support, a blank support, means for rotating the hob and blank in intermeshing timed relation and means for simultaneously imparting a relative rolling movement between the hob and blank supports.
53. In a machine for producing gears, a 60 hob support, a hob of constant pitch rotatably mounted thereon, a blank support, means for rotating the hob and blank in intermeshing timed relation, and means for simultaneously imparting a relative rolling movement between the hob and blank supports.
54. In a machine for producing gears, a 70 hob support, a taper hob of constant pitch rotatably mounted thereon, a blank support, means for rotating the hob and blank in intermeshing timed relation, and means for simultaneously imparting a relative rolling movement between the hob and blank supports in the manner of a gear meshing with a crown gear.
55. In a machine for producing gears, a 75 hob support, a taper hob rotatably mounted thereon, a blank support adapted to carry a tapered gear blank, means for rotating the hob and blank in intermeshing timed relation, and means for simultaneously imparting a relative rolling movement between the hob and blank supports in the manner of a gear meshing with a crown gear.
56. In a machine for producing gears, a 80 hob support, a taper hob of constant pitch rotatably mounted thereon, a blank support adapted to carry a tapered gear blank, means for rotating the hob and blank in intermeshing timed relation, and means for simultaneously imparting a relative rolling motion between the hob and blank supports in the manner of a gear meshing with a crown gear.
57. In a machine for producing gears by 85 relative movement of tool and blank in the manner of relative intermeshing rotation between a crown gear and the gear to be cut, in combination, a blank support, a tool support, a taper hob rotatably mounted on the hob support, means for positioning the tool and blank support relatively to each other so that the apex of the blank lies at the center of the imaginary crown gears, means for positioning the hob support and blank support, so that the hob and blank are tangent to a common plane with the hob axis offset from the center of said imaginary 90 crown gear, means for rotating the hob and blank in intermeshing timed relation, and means for simultaneously imparting a relative rolling movement between the hob and blank supports above at an axis passing through the center of said imaginary crown gear.
58. In a machine for producing gears by 95 a relative movement of tool and blank in the manner of relative intermeshing rotation between a crown gear and a gear to be cut, in combination, a blank support, a hob support, a hob of constant pitch rotatably mounted on said hob support, means for positioning the blank and hob supports relatively to each other so that the apex of the blank lies at the center of the imaginary crown gear means for positioning the hob and blank supports so that the hob and blank are tangent to a common plane with the hob axis offset from the center of said imaginary crown gear, means for rotating the hob and blank in intermeshing timed relation, and means for simultaneously imparting a relative rolling movement between the hob and blank supports about an axis passing through the center of said imaginary crown gear.
59. In a machine for producing gears by 100 105 110 115 120 125 130

a relative movement of tool and blank in the manner of relative intermeshing rotation between a crown gear and a gear to be cut, in combination, a blank support, a hob support, a taper hob of constant pitch rotatably mounted on said hob support, means for positioning the hob and blank supports relatively to each other so that the apex of the blank lies at the center of the imaginary crown gear, means for positioning the hob and blank supports so that the hob and blank are tangent to a common plane with the axis of the hob offset from the center of said imaginary crown gear, means for rotating the hob and blank supports in intermeshing timed relation and means for simultaneously imparting a relative rolling movement between the hob and blank supports about an axis passing through the center of said imaginary crown gear.

60. In a machine for producing gears, a blank support, a taper hob, means for rotating the hob and blank in intermeshing timed relation and means for simultaneously moving the hob about the apex of the blank at a constant radial distance therefrom.

61. In a machine for producing gears, a blank support, a hob of constant pitch, means for rotating the hob and blank in intermeshing timed relation, and means for simultaneously moving the hob about the apex of the blank at a constant radial distance therefrom.

62. In a machine for producing gears, a blank support, a taper hob of constant pitch, means for rotating the hob and blank in intermeshing timed relation and means for simultaneously moving the hob about the apex of the blank at a constant radial distance therefrom.

63. In a machine for producing gears, a rotary blank support adapted to carry a tapered gear blank, a hob support, a worm hob rotatably mounted on said hob support, a cradle upon which one of said supports is mounted, means for rotating the hob and blank in intermeshing timed relation, means for simultaneously rotating the cradle on its axis and compensating means for maintaining the timed relation of the hob and blank rotation during the movement of said cradle.

64. In a machine for producing gears, a rotary blank support adapted to carry a tapered gear blank, a hob support, a taper hob rotatably mounted thereon, a rotatable cradle upon which one of said supports is mounted, means for rotating the hob and blank in intermeshing timed relation, means for simultaneously rotating the cradle on its axis, and compensating means for maintaining the timed relation of the hob and blank rotation during the movement of said cradle.

65. In a machine for producing gears, a rotary blank support adapted to carry a tapered gear blank, a hob support, a hob of constant pitch rotatably mounted thereon, a rotatable cradle upon which one of said supports is mounted, means for rotating the hob and blank in intermeshing timed relation, means for simultaneously rotating the cradle on its axis, and compensating means for maintaining the timed relation of hob and blank rotation during the movement of said cradle.

66. In a machine for producing gears, a rotary blank support adapted to carry a tapered gear blank, a hob support, a taper hob of constant pitch rotatably mounted thereon, a rotatable cradle upon which one of said supports is mounted, means for rotating the hob and blank in intermeshing timed relation, means for simultaneously rotating the cradle on its axis, and compensating means for maintaining the timed relation of hob and blank rotation during the movement of said cradle.

67. In a machine for producing gears, a rotary blank support adapted to carry a tapered gear blank, a hob support, a worm hob rotatably mounted thereon, a rotary cradle upon which one of said supports is mounted, means for adjusting said hob support to offset the axis of the hob relative to the axis of said cradle, means for rotating the hob and blank in intermeshing timed relation, means for simultaneously rotating the cradle on its axis, and compensating means for maintaining the timed relation of the hob and blank rotation during the movement of said cradle.

68. In a machine for producing gears, a rotary blank support adapted to carry a tapered gear blank, a hob support, a taper hob rotatably mounted thereon, a rotatable cradle upon which one of said supports is mounted, means for adjusting said hob support to offset the axis of said hob relative to the axis of said cradle, means for rotating the hob and blank in intermeshing timed relation, means for simultaneously rotating the cradle on its axis, and compensating means for maintaining the timed relation of hob and blank rotation during the movement of said cradle.

69. In a machine for producing gears, a rotary blank support adapted to carry a tapered gear blank, a hob support, a hob of constant pitch rotatably mounted thereon, a rotary cradle upon which one of said supports is mounted, means for adjusting said hob support to offset the axis of the hob relative to the axis of said cradle, means for rotating the hob and blank in intermeshing timed relation, means for simultaneously rotating the cradle on its axis, and compensating means for maintaining the timed

relation of the hob and blank rotation during the movement of said cradle.

70. In a machine for producing gears, a rotary blank support adapted to carry a tapered gear blank, a hob support, a taper hob of constant pitch rotatably mounted thereon, a rotary cradle upon which one of said supports is mounted, means for adjusting said hob support to offset the axis of the hob relative to the axis of the cradle, means for rotating the hob and blank in intermeshing timed relation, means for simultaneously rotating the cradle on its axis, and compensating means for maintaining the timed relation of the hob and blank rotation during the movement of said cradle.

71. In a machine for producing gears, a rotary blank support adapted to carry a tapered gear blank, a hob support, a worm hob rotatably mounted thereon, a rotary cradle, upon which one of said supports is mounted, angularly movable about an axis extending through the apex of the blank, means for rotating the hob and blank in intermeshing timed relation, means for simultaneously rotating the cradle on its axis, and compensating means for maintaining the timed relation of hob and blank rotation during the movement of said cradle.

72. In a machine for producing gears, a rotary blank support adapted to carry a tapered gear blank, a hob support, a taper hob rotatably mounted thereon, a rotary cradle, upon which one of said supports is mounted, angularly movable about an axis extending through the apex of the blank, means for rotating the hob and blank in intermeshing timed relation, means for simultaneously rotating the cradle on its axis, and compensating means for maintaining the timed relation of hob and blank rotation during the movement of said cradle.

73. In a machine for producing gears, a rotary blank support adapted to carry a tapered gear blank, a hob support, a hob of constant pitch rotatably mounted thereon, a cradle, upon which one of said supports is mounted, angularly movable about an axis extending through the apex of the blank, means for rotating the hob and blank in intermeshing timed relation, means for simultaneously rotating the cradle on its axis, and compensating means for maintaining the timed relation between the hob and blank rotation during the movement of said cradle.

74. In a machine for producing gears, a rotary blank support adapted to carry a tapered gear blank, a hob support, a taper hob of constant pitch rotatably mounted thereon, a rotary cradle, upon which one of said supports is mounted, angularly movable about an axis extending through the apex of the blank, means for rotating the hob and blank in intermeshing timed relation,

means for simultaneously moving the cradle, 65 on its axis, and compensating means for maintaining the timed relation between the hob and blank rotation during the movement of said cradle.

75. In a machine for producing gears, a 70 rotary blank support adapted to carry a tapered gear blank, a hob support, a taper hob rotatably mounted thereon, means for adjusting the hob support to offset the hob axis relative to the apex of the blank, and 75 means for adjusting the hob axially to vary its position relative to the cone apex of the blank.

76. In a machine for producing gears, a 80 rotatable blank support adapted to carry a tapered gear blank, a tool support, a hob of constant pitch rotatably mounted thereon, means for adjusting the tool support to offset the axis of the hob relative to the apex 85 of the blank and means for adjusting the hob longitudinally of its axis.

77. In a machine for producing gears, a 90 rotatable blank support adapted to carry a tapered gear blank, a hob support, a taper hob of constant pitch rotatably mounted thereon, means for adjusting the hob support to offset the axis of the hob relative to the apex 95 of the blank and means for adjusting the hob longitudinally of its axis.

78. In a machine for producing gears, a 100 rotatable blank support adapted to carry a tapered gear blank, a rotary cradle, a hob support pivotally mounted on said cradle for adjustment about an axis offset from the axis of said cradle, and a taper hob rotatably mounted on said hob support.

79. In a machine for producing gears, a 105 rotatable blank support adapted to carry a tapered gear blank, a rotary cradle, a hob support pivotally mounted on said cradle for adjustment about an axis offset from the axis of said cradle, and a hob of constant pitch rotatably mounted on said hob support.

80. In a machine for producing gears, a 110 rotatable blank support, adapted to carry a tapered gear blank, a rotary cradle, a hob support pivotally mounted on said cradle for adjustment about an axis offset from the axis of said cradle, and a taper hob of constant pitch rotatably mounted on said hob support.

81. In a machine for producing gears, a 115 rotatable blank support adapted to carry a tapered gear blank, a rotary cradle, a hob support pivotally mounted on said cradle for adjustment about an axis offset from the axis of said cradle, and a taper hob rotatably mounted on said hob support and axially adjustable thereon.

82. In a machine for producing gears, a 120 rotatable blank support adapted to carry a tapered gear blank, a rotary cradle, a hob

support pivotally mounted on said cradle for adjustment about an axis offset from the axis of said cradle, and a hob of constant pitch rotatably mounted on said hob support and axially adjustable thereon.

83. The method of cutting longitudinally curved tooth tapered gears which consists in applying power through a uniformly operating driving mechanism to rotate a taper 10 hob and a tapered gear blank on their respective axes, simultaneously imparting a relative rolling movement between the hob and blank, and applying power additionally through a differentially operating driving mechanism to one of said bodies to maintain the rotation of the hob in continuously operative timed relation to the rotation of the blank.

84. The method of cutting longitudinally 20 curved tooth tapered gears which consists in applying power through a uniformly operating driving mechanism to rotate a hob of constant pitch and a taper gear blank on

their respective axes, simultaneously imparting a relative rolling movement between the 25 hob and blank and applying power additionally through a differentially operating driving mechanism to one of said bodies to maintain the rotation of the hob in continuously operative timed relation to the rotation 30 of the blank.

85. The method of cutting longitudinally curved tooth tapered gears, which consists in applying power through a uniformly operating driving mechanism to rotate a taper 35 hob and a tapered gear blank on their respective axes, simultaneously imparting a relative rolling movement between the hob and blank and applying power additionally through a differentially operating driving 40 mechanism to one of said bodies to maintain the rotation of the hob in continuously operative timed relation to the rotation of the blank.

In testimony whereof I affix my signature.
NIKOLA TRBOJEVICH.
